Patented Dec. 22, 1925.

UNITED STATES PATENT OFFICE.

ORA H. JUSTUS, OF PARKERSBURG, WEST VIRGINIA.

PURIFIER FOR GASOLINE SYSTEMS.

Application filed June 12, 1924. Serial No. 719,639.

To all whom it may concern:

Be it known that I, ORA H. JUSTUS, citizen of the United States, residing at Parkersburg, in the county of Wood and 5 State of West Virginia, have invented certain new and useful Improvements in Purifiers for Gasoline Systems, of which the following is a specification.

This invention relates to certain new and 10 useful improvements in purifiers for gasoline systems and pertains more particularly to an improvement on the bottle holder disclosed in my Patent No. 1,464,822, issued August 14, 1923.

15 The primary object of the present invention is to provide a more simplified and economical form of bottle holder and wherein but a single pair of bolts and nuts are employed to secure the holder in position, as 20 distinguished from the two pairs of bolts and nuts disclosed in my said patent.

A further object of the present invention, 25 is to provide a bottle holder which embodies similar complementary sections that may be formed from the same dies and which are supported by a single pair of bolts, whereby upon disengagement of either bolt, the sections may be relatively swung apart about the other bolt as a pivot, thereby to enable 30 the bottle to be easily and quickly removed and replaced.

The invention has still further and other objects which will be later set forth and manifested in the course of the following description.

In the drawings:—

Figure 1, is a front elevation of the invention;

Figure 2, is a top plan view thereof;

40 Figure 3, is a side elevation, and

Figure 4, is a section on line 4—4 of Figure 1.

The bracket, which is of L-shape has its vertical member 1 formed with apertures 2 45 to receive fastenings for securing same to the dash of an automobile beneath the hood thereof, while the horizontal part or table 3 of the bracket is provided with nipples 4 and 5, nipple 4 constituting the inlet and nipple 5 the outlet, the latter leading to the carbureter or to the vacuum tank in the instance of vacuum systems. A fine mesh 50 strainer 6 is connected to the nipple 5, which latter and the nipple 4 are surrounded by 55 a washer or gasket 7 that is engaged against

the under face of the table 3 and with the mouth of the bottle or container 8. All of the above described parts are disclosed in my said patent, the present invention relating particularly to the bottle holder, now to be 60 described.

A pair of similar complementary bottle clamping sections 9 and 10 are employed, which latter have substantially semi-circular central parts that engage about the bottle neck and beneath the bead 11 thereof. The section 9 has a lower eye 12 and an upper eye 13, while the section 10 has an upper eye 14 seated upon and registering with eye 12 and a lower eye 15 registering with 70 and supporting eye 13 of the clamp 9. The eyes are formed by reducing the width of the ends of the sections and then curling or bending the reduced parts into substantially 75 circular form.

Vertical suspension bolts 16 and 17 project through the registering eyes 12 and 14 and 13 and 15 respectively and have their heads engaged with the eyes 12 and 15 respectively while their threaded ends project through the table 3 and are equipped with wing nuts 18, by tightening of which, the upper end of the bottle neck is engaged with the washer and the latter tightly impinged against the under face of the table, thereby sealing the mouth of the bottle against the ingress of air.

From the foregoing it will be obvious that by removal of either wing nut 18 and subsequent removal of either bolt 16 or 17, the sections 9 and 10 may be swung about the remaining bolt as a pivot or pintle, thereby enabling the bottle to be easily and quickly removed and replaced, which removal is periodically necessitated in order to cleanse 90 the bottle of the accumulated sediment or dirt separated by the strainer from the gasoline in the passage of the latter through the bottle.

The sections of the bottle clamps are similar in all respects and are thus interchangeable, enabling the same set of dies to be employed in manufacture of the sections of the clamp.

The present invention thus enables complete removal of the bottle by disengagement of but one bolt, as distinguished from my former invention, wherein each of the two vertical bolts must be removed, and in the patent and in the instance of applying a 110

new bottle, the two horizontal bolts must also be removed to permit the clamp to be applied to a new bottle.

The bolts 16 and 17 thus function in a dual manner, namely they afford means of suspension of the clamp, and thereby the bottle, from the support, and further afford pintles about which the clamp sections may be swung to release the bottle.

10 What is claimed is:

A bottle holder comprising in combination with a support, a clamp including sections formed to engage about opposite sides of the bottle neck and against the bead there-
15 of, an eye at each end of each section, the

eyes at adjacent ends of the sections being in register, and a pair of bolts extending through the registering eyes at the respective clamp ends and through the support and having nuts thereon engaged with the support to clamp the bottle mouth against the support, the eyes being formed so that upon removal of either bolt, the clamp sections may be pivotally swung about the remaining bolt as a pivot to release the bottle and while the remaining bolt remains in position to support the clamp.

In testimony whereof I affix my signature.
ORA H. JUSTUS.
